UNITED STATES PATENT OFFICE.

GLENN J. BARRETT, OF SYRACUSE, NEW YORK, ASSIGNOR TO THE SMITH PREMIER TYPE-WRITER COMPANY, OF SYRACUSE, NEW YORK, A CORPORATION OF NEW YORK.

TYPE-WRITING MACHINE.

No. 902,131.

Specification of Letters Patent.

Patented Oct. 27, 1908.

Application filed May 21, 1908. Serial No. 434,078.

To all whom it may concern:

Be it known that I, GLENN J. BARRETT, citizen of the United States, and resident of Syracuse, in the county of Onondaga and 5 State of New York, have invented certain new and useful Improvements in Type-Writing Machines, of which the following is a specification.

My invention relates to typewriting machines and particularly to escapement mechanism for the carriages of such machines.

My invention is in the nature of an improvement on the escapement shown and described in the application of John H. Barr 15 filed April 7th, 1908, Serial No. 425,687 and it has for its principal object to provide an escapement that is simple in construction and positive in its action and that affords a quick let-off to the carriage.

20 A still further object of my invention is to provide means whereby the necessity of securing an equal leverage of all the typewriter key levers on the escapement mechanism is avoided; to provide such mechanism wherein the escapement will take place 25 immediately upon the starting of the type bar backward after impinging no matter where the "drop" or disengagement of the normal retaining dog from the wheel occurs; to provide a positive means for accomplishing these results, and such other 30 further objects as will hereinafter appear.

To the above and other ends, my invention consists in certain features of construction 35 and combinations and arrangements of parts, all of which will be fully set forth herein and particularly pointed out in the claims.

In the accompanying drawings, Figure 1 40 is a rear elevation showing so much of a typewriting machine as is necessary to illustrate the application of my invention thereto. Fig. 2 is an enlarged isometric view of the preferred form of my invention. 45 Figs. 3, 4 and 5 are top plan views of the escapement, the parts being shown in normal position in Fig. 3 and in Fig. 4 in the position they occupy when a key is fully depressed, and in Fig. 5 in a position they 50 occupy during the up-stroke of the key and after the escapement or let-off has taken place. In Figs. 4 and 5 certain springs are omitted in order not to obscure the other parts. Fig. 6 is a fragmentary top view of

the connection between the universal bar or 55 gate and the dog-carrying rock shaft. Fig. 7 is a fragmentary top plan view of part of a typewriter showing a modified form of escapement made in accordance with my invention, the parts being shown in normal 60 position. Fig. 8 is a rear elevation of the same. Fig. 9 is a top view of some of the parts shown in Fig. 7, but shown in the positions they occupy when a key is fully depressed. Fig. 10 is a view similar to Fig. 65 9 but showing the parts in positions they occupy during the up-stroke of a key just after the escapement or let-off has taken place. Fig. 11 is a rear view of part of the escapement shown in Fig. 7, the dogs being 70 shown in section. Fig. 12 is a detail view of a wedge member forming part of the escapement shown in Fig. 7. Fig. 13 is a top plan view, partly in section, showing another modification. Fig. 14 is a rear elevation of the same. Fig. 15 is a fragmentary top plan view, showing feed dogs adapted 75 for use in connection with the devices shown in Figs. 13 and 14.

My invention is applicable to typewriting 80 machines generally, but I have here shown it applied to a Smith Premier typewriter. The main frame of this machine consists of side plates 1 having posts 2 rising therefrom and supporting an upper framework 3 85 which, for convenience, will herein be designated as a top plate. The side plates 1 are connected together at the rear by a back plate 4. A carriage is mounted on the top plate in the usual manner and has a feed 90 rack which is geared to an escapement wheel or rack 5 in such fashion that said wheel, when the carriage is moving in letter space direction, turns in the direction of the arrow 95 in Fig. 1. The printing keys 6 are each connected to one of a series of rock shafts 7, each of which rock shafts has an arm that actuates a type bar. Each of the rock shafts also has an arm 8 which operates a universal 100 bar or gate 9 in a well-known manner, moving said gate toward the left in Fig. 1. The gate 9 is mounted on links 10 which are pivoted at 11 to the back plate 4 and the universal bar is restored to normal position by a spring 12. A bifurcated bracket 13, rising 105 from the universal bar, is bent at its upper part toward the rear of the machine to embrace a grooved disk 14 which is mounted

on an arm 15 projecting from a vertical rock shaft 16, which at its lower end is pivoted in the plate 4 and at its upper end is pivoted or journaled in the top plate 3. The construction is such that when a key is struck the rock shaft 16 is oscillated.

Above the top plate 3 a horizontally disposed plate-like arm 17 is rigidly mounted on the upper end of the shaft 16, and above the plate 17 two feed dogs 18 and 19 are pivotally mounted on the shaft and project therefrom toward the left of the operator into position for engagement with the escapement wheel 5. The dog 18 lies on top of the plate 17 and at its pivotal end the dog 19 lies on top of the dog 18, both of said dogs being pivoted on a shouldered and headed pivot screw 20 which is threaded into the upper end of the shaft 16. At its free or working end the dog 19 is depressed so as to bring the rear edge thereof in front of the forward edge of the dog 18 and so as to bring the working face of the dog 19 nearly, but not quite, down to the level of the working face of the dog 18, so as to leave a slight "drop" from the dog 19 to the dog 18. These two dogs are independently pivoted but they tend to move together, this tendency being due to a contractile spring 21 which is connected at its ends to posts or pins 22 and 23 rising from the dogs 18 and 19, respectively. The relative motion of the two dogs under the impulse of the spring 21 is limited by the contact of the rear edge of the dog 19 with the forward edge of the dog 18. The dog 18 has an arm 24 projecting therefrom toward the front of the machine and said arm has a rounded nose 25, the rounded edge of which contacts with the edge of an eccentric, or pivoted wedge or take-up device 26 which is pivoted to the plate 17 by a pivot screw 27. A post or pin 28 rises from the arm 24 and the member 26 is provided with a similar pin 29 and said pins are connected by a contractile spring 30 which normally maintains the nose 25 pressed against the end of the pivoted take-up member 26.

The free end of the wedge device 26 has a cut-out or notch therein, as indicated at 31, and the part 32 of the free edge of said device is formed eccentric to the pivotal center of the device 26 so that said edge 32 is adapted to act like a wedge in taking up lost motion between the nose 25 and the pivot screw 27 as will more clearly appear presently. In the normal position of the parts the nose 25 is seated in the notch or cut-out 31 as indicated in Figs. 2 and 3.

The wedge device 26 has a resetting arm 33 which is adapted to contact with an abutment consisting of a pin or arm 34 bent upward from a plate 35 of sheet metal which is adjustably secured to the top plate 3 by screws 36 which are threaded into the top

plate and which pass through holes in the plate 35 of such dimensions as to admit of some adjustment of the plate. The device 26 also has an arm 37 adapted to contact with the dog 18 to prevent the device from being accidentally turned too far about its pivot.

The dog 18 is formed with a stop projection 38 which when a key is depressed is adapted to strike against the web of the escapement wheel 5 and to arrest the forward motion of the dog. It will be noted that this forward projection is of such character as to admit of the dog 18 entering into only a slight engagement with a tooth of the escapement wheel 5.

When the parts are in normal position, as indicated in Fig. 3, the dog 19 is in engagement with the wheel 5, the nose 25 rests in the notch 31 and the arm 33 is in contact with the fixed stop or abutment 34. When a key is depressed the shaft 16 is rocked, carrying with it the plate 17 which is rigidly secured to it. During the first part of the motion of the shaft the dog 18 moves with the shaft, being operated by the spring 30 acting on the arm 24 of said dog, but the dog is arrested in its forward motion by the stop projection 38 before the shaft 16 completes its forward stroke. During the remainder of the forward stroke of the shaft 16 and plate 17 the distance of the pivot screw 27 from the nose 25 is increased so that the device 26 moves to such a position as to bring the notch 31 thereof out of engagement with the nose 25 and to bring the eccentric edge 32 into contact with said nose.

It will be understood that as soon as the shaft begins its forward stroke the arm 33 moves away from the abutment 34 and when the dog 18 is arrested the device 26 is turned about its pivot 24 by the spring 30, which spring keeps the operative end of the wedge device pressed against the nose 25 of the dog. The extent to which the wedging device will be turned about its pivot will depend upon the extent of motion of the shaft 16 after the dog 18 is arrested. If the shaft has but little motion after said dog is arrested, the wedging device will move but little about its pivot, whereas if there is a greater extent of additional motion of the shaft the wedging device will drop to a greater extent toward the rear of the machine; and in any event whatever amount of additional motion the shaft 16 may have over and above the motion of the dog 18, this additional motion will be automatically taken up by the wedging device. The result is that whether the shaft 16 has moved comparatively far or comparatively little, the instant the shaft begins its return stroke the wedging device will force the dog 18 to move with it, and will immediately move said dog out of engagement with the escapement wheel. It will

100

thus be seen that the point at which the escapement or let-off takes place in the return stroke of the parts is uniform and is independent of the point in the forward stroke 5 of the parts at which the "drop" occurred. The extent of motion of the shaft 16 may vary from different causes; for example, the shaft is moved a little further when a key is struck with considerable force than it is when 10 the key is struck more gently. Moreover, if the several arms 8 do not have precisely the same relation to the universal gate 9 some of these arms will operate the universal bar and turn the shaft a little further than others. 15 It will be seen that by the use of the present escapement any fine and accurate adjustment of each of these arms 8 with relation to the universal bar is rendered unnecessary as the escapement mechanism automatically 20 adjusts itself to any variations in the motion of the universal bar, so that the escapement takes place at the same point in the up-stroke of the different keys even though said keys may not take up the universal bar at 25 the same points in their respective down strokes. As the stop 38 allows the dog to enter the wheel only a very short distance and as the dog begins to move out of engagement with the wheel in the very first part of 30 the return motion of the dog rocker, it will be seen that the escapement or let-off takes place very early in the return stroke of a key.

At their working ends the dogs 18 and 19 are spaced apart a distance less than the 35 thickness of a tooth of the wheel 5. On the return stroke of the dog rocker the dog 18 is positively moved out of engagement with the wheel and the dog 19 is drawn after it by the spring 21. As the working face of 40 the dog 19 is a little higher than that of the dog 18, the rear edge of the dog 19 will contact with the forward face of the tooth of the escapement wheel and said dog 19 will be arrested, the dog 18 moving on toward 45 the rear independently until the space between the two dogs is wide enough to let the tooth pass through. As soon as the tooth passes the dogs, the dog 19 snaps in behind it under the impulse of the spring 21 and arrests the next succeeding tooth of the wheel. 50 This operation, as has been explained above, takes place during the first part of the return motion of the dog rocker. As soon as the arm 33 strikes the abutment 34 on the 55 return stroke of the dog rocker the further motion said rocker restores the wedging device 26 to its normal position shown in Fig. 3, and the nose 25 is drawn back into the notch 31 by the spring 30. Fig. 4 shows the position of the parts when a key is fully 60 depressed and Fig. 5 shows the position they occupy just after the escapement has taken place and just as the arm 33 in its return stroke has reached the abutment 34. 65 The remainder of the return stroke of the

shaft 16 restores the parts from the positions shown in Fig. 5 to those shown in Fig. 3.

Various changes may be made in the details of construction and arrangement without departing from my invention. For example, in Figs. 7 to 12 inclusive I have shown a modification in which the plate 17 and the dogs 18 and 19 are like those above described except that the arm 24 of the dog 18 is somewhat different in that the nose 25 is omitted and instead thereof I mount a roller 40 on the pin 28, which roller is engaged by the free end of the pivoted wedging device 26 in the same manner as the nose 25 in the other form, said device 26 being bent upward at its free end in order to bring it into position to coöperate with the roller 40. Said device 26 in this form of the invention is provided with a forwardly extending arm 41 from which the pin 29 rises and said forwardly extending arm has a radially disposed edge 42 which contacts with a pin 43 rising from the top plate 3. This pin 43 is a restoring pin to restore the pivoted wedging device to normal position during the latter part of the return stroke of the dog rocker in a manner which will be understood from the description of the first form of the invention. In this form of the invention there is a certain amount of friction caused by the rubbing of the edge 42 against the pin 43 which is obviated in the preferred form shown in Figs. 1-6, by reason of the fact that in said preferred form 100 the abutment 34 is substantially in alignment with the centers of the screws 27 and 20.

In Fig. 11 I have illustrated some of the details of the mounting of the plate 17 and the dogs 18 and 19. As shown in this figure the screw 20 is doubly shouldered or formed with annular steps 44 and 45. The step 44 is screwed down tight against the plate, thus rigidly securing said plate to the top of the shaft. The dog 18 is pivoted on this step 110 44 and is retained against displacement by the larger step 45, on which larger step the dog 19 is pivoted and retained in position by the head of the screw. A cap or collar 46 has a taper fit on the upper end of the shaft 16 in order to give a wider bearing surface for the plate 17. It will be understood that the mounting of the dogs as shown in Fig. 1 may be the same as that shown in Fig. 11.

In Fig. 12 I have shown a detail view of the pivoted wedging device. In this figure *a* is an arc having radius *b* and its center at the center of the pivot screw 27, and *d* is an arc including the edge 32, said arc *d* having radius *c* and center *f*, the center *f* being forward of the center of the pivot screw. The angle or opening between the arcs *a* and *d* shows the wedging effect of the eccentric 125 contacting edge 32.

The lost motion between the dog and keys may be taken up at some other point than that above described. In Figs. 13, 14 and 15 I have shown a form of my invention in which the shaft 16 itself is arrested when the holding dog has moved a sufficient distance into engagement with the wheels and where the pivoted wedge or take-up member forms part of the connection between the universal bar 9 and the shaft. In this form of my invention the escapement dogs may be made in any one of a variety of ways, the preferred construction being shown in Fig. 15. In this construction, the holding dog 18 is provided with a stop extension 38 as in the other forms of the invention, but said holding dog is rigidly mounted on the shaft 16, the plate 17 being dispensed with. The arm 24 and the member 26 also are not used in this construction. The dog 19 is pivoted on the screw 20 and is connected with the dog 18 by the spring 21 as before. The shaft 16 has an arm or crank 46 which is controlled by a wedging arm or plate 47, pivoted on a screw 48 threaded into an ear 49 bent back toward the rear of the machine from the upper part of a bracket 50 extending upward from the universal bar 9. This plate 47 has an eccentric contact edge 51 similar in disposition and functions to that of the eccentric edge 32 of the member 26 in the other forms of the invention, the edge 51 being in contact with the crank 46. A contractile spring 52 connects said crank 46 with a pin 53 projecting from the plate 47 in front of the screw 48. The construction is such that when, by the depression of a key, the gate 9 is moved in the direction of the arrow in Fig. 13, the crank 46 is drawn in the same direction by the spring 52 until the shaft 16 is arrested by the contact of the stop 38 with the escapement wheel, thus arresting the crank 46. After this the universal bar continues its motion stretching the spring 52 and moving the pivot 48 to a greater distance from the crank 46. The plate 47 is rocked about its pivot 48 by the spring 52 to whatever extent is necessary to take up this additional motion of the gate 9. When the key is released and the universal bar begins its return motion the plate 47 acts as a positive connection between the universal bar and the crank 46, causing said crank to rock the shaft 16 during the first part of the return motion of the universal bar. The free end of the plate 46 is formed with a cam edge 54 which on the return motion of the universal bar contacts with the shaft 16 and cams the plate 46 back to the position shown in Fig. 13 where it is arrested in normal position ready for another operation at the next depression of a key. It will be seen that this form of the invention works on the same principle as the prior forms but that the take-up of

the lost motion occurs at a different point in the chain of connections between the keys and escapement dogs.

I have referred in the accompanying claims to the "forward" and "return" stroke of the "actuator". This does not mean the direction of movement but means the movements of the "actuator", universal bar or gate during the depression of a key and during the return movement thereof respectively.

What I claim as new and desire to secure by Letters Patent, is:—

1. In a typewriting machine, escapement devices including an actuator, a dog movable with said actuator, said dog and actuator also being relatively movable, a device automatically operative to take up the lost motion between the actuator and said dog, and means for resetting said device operated directly by a return movement of the actuator.

2. In a typewriting machine and in escapement mechanism, the combination with a dog and an actuator for said dog, said actuator being movable independently of said dog, of a wedge device for taking up lost motion between said dog and said actuator, said wedge device comprising a pivoted piece having an eccentric edge which acts as a wedge.

3. In a typewriting machine and in escapement mechanism, the combination with a dog and an actuator for said dog, said actuator being movable independently of said dog, of a wedge device movably connected with said actuator for taking up lost motion between said dog and said actuator, and a stop against which said wedge device is moved by the actuator, said stop co-operating with said wedge device to restore the same to normal position relatively to said dog.

4. In a typewriting machine and in escapement mechanism, the combination with a dog and an actuator for said dog, said actuator being movable independently of said dog, of a two-armed piece pivoted to said actuator, one of the arms of said piece having an eccentric edge which acts as a wedge to take up lost motion between said dog and said actuator, a part connected with said dog and co-operating with said eccentric edge, and a stop co-operating with the other arm of said pivoted piece to restore the same to normal position relatively to said dog.

5. In a typewriting machine and in escapement mechanism, the combination of a dog, an oscillatory dog actuator movable independently of said dog, an arm rigid on said actuator, an automatically operating wedge device pivoted to said arm and operating to take up lost motion between said actuator and said dog, and a fixed stop for restoring said wedge device to normal position relatively to said dog.

6. In a typewriting machine and in escape-

ment mechanism, the combination of two dogs, an actuator for said dogs, means for arresting both of said dogs before said actuator completes its forward stroke, an automatically operating wedge device for taking up the lost motion between said dogs and said actuator whereby the dogs are started on their return stroke when the actuator first begins its return stroke, and means for automatically restoring said wedge device to normal position.

7. In a typewriting machine and in escapement mechanism, the combination of a dog; an actuator for said dog; means for moving said dog with said actuator during the first part of the forward stroke of said actuator; means for arresting said dog before said actuator completes its forward stroke; an abutment connected with said dog; an automatically operating wedge device co-operating with said abutment for taking up the lost motion between said dog and said actuator whereby the dog is started on its return stroke when the actuator first begins its return stroke, said wedge device comprising a pivoted member having an eccentric edge which contacts with said abutment; and means for automatically restoring said wedge device to normal position.

8. In a typewriting machine and in escapement mechanism, the combination of a dog, an actuator for said dog, means for moving said dog with said actuator during the first part of the forward stroke of the latter, means for arresting said dog before said actuator completes its forward stroke, an automatically operating wedge device for taking up the lost motion between said dog and said actuator and for positively moving said dog with said actuator during the first part of the return stroke of the actuator, and a fixed abutment against which said wedge device impinges during the latter part of the return stroke of the actuator, whereby said wedge device is restored to normal position relatively to said dog.

9. In a typewriting machine and in escapement mechanism, the combination with an escapement rack, of a feed dog, an actuator for said feed dog, a wedge device interposed between said actuator and said dog, a spring normally holding said dog in contact with said wedge device, means for arresting said dog before said actuator completes its forward stroke, and means for arresting said wedge device before said actuator completes its return stroke, said wedge device operating automatically to take up the lost motion between the actuator and the dog during the latter part of the forward stroke of the actuator and said wedge device being restored to normal position relatively to the feed dog by the means which arrests it during the return stroke of the actuator.

10. In a typewriting machine and in escapement mechanism, the combination with a rack, of a feed dog, an actuator for said feed dog, means for arresting said dog before said actuator completes its forward stroke, a wedge device, spring means for pressing said wedge device and said dog together whereby said wedge device is adapted to take up the lost motion between the dog and the actuator during the latter part of the forward stroke of the actuator, and an abutment for restoring said wedge device to normal position relatively to the dog during the latter part of the return stroke of the actuator.

11. In a typewriting machine and in escapement mechanism, the combination of a dog rocker, an arm rigidly mounted on said dog rocker, a feed dog pivotally mounted on said dog rocker, means for arresting said dog before the dog rocker completes its forward stroke, a spring pressed take-up device pivoted to said arm for taking up the lost motion between the dog and the dog rocker, and an adjustable fixed abutment for restoring said take-up device, said abutment and the pivotal centers of said take-up device and of said dog-rocker being substantially in alinement.

12. In a typewriting machine, the combination of an oscillating dog carrier, escapement dogs movably mounted upon said dog carrier, a stop for limiting the oscillation of said dogs without limiting the oscillation of said dog carrier, a wedging arm pivotally mounted upon said dog carrier, an abutment on one of said escapement dogs adapted to contact with said wedging arm, a spring extending from said wedging arm at a point eccentric to the pivotal point of said wedging arm and connected with said dog, and a stop for positioning said wedging arm on the dog carrier.

13. In a typewriting machine, the combination of an oscillating dog carrier, dogs movably mounted upon said dog carrier, means for holding said dogs in normal relation to each other, a stop for limiting the oscillation of said dogs without limiting the oscillation of said dog carrier, a swinging arm pivotally mounted upon said dog carrier, a roller carried by one of said escapement dogs and adapted to contact with said swinging arm, a spring between said dog carrying said roller and said swinging arm, and a stop for positioning said swinging arm on said dog carrier.

14. In a typewriting machine, the combination of an oscillating dog carrier, dogs movably mounted upon said dog carrier, means for holding said dogs in normal relation to each other, means for limiting the oscillation of said dogs without limiting the oscillation of said dog carrier, a swinging arm movably mounted upon said dog carrier

and adapted to contact with one of said dogs, a spring between said swinging arm and the one of said dogs which contacts with said swinging arm, and means for normally positioning said swinging arm.

15. In a typewriting machine, the combination of an oscillating dog carrier, dogs movably mounted upon said dog carrier, a spring for moving said dogs with said dog carrier in one direction, a stop for limiting the motion of said dogs in said one direction before said dog carrier shall have completed its motion, a positive means for connecting said one of said dogs to said dog carrier during the earlier part of the return movement of said dog carrier toward normal position, consisting of a wedging arm pivotally mounted upon said dog carrier and a spring adapted to force said wedging arm against one of said dogs; and a suitable stop for removing the wedging portion of said wedging arm from the said one of said dogs when said dog carrier returns to normal position.

25. 16. In a typewriting machine, the combination of an oscillating dog carrier, dogs movably mounted upon said dog carrier, a spring for moving said dogs with said dog carrier in one direction, a stop for arresting the movement of one of said dogs in one direction, and before said dog carrier completes its movement in the same direction, a wedging device carried by said dog carrier and adapted to contact with one of said dogs when said dog carrier completes the first half of the movement, and a fixed stop for returning said wedging device to normal position on said dog carrier.

17. In a typewriting machine, the combination of an oscillating dog carrier, two dogs movable with and independently of said dog carrier, a spring for moving said dogs with said dog carrier in one direction, a stop for arresting the movement of both of said

dogs in one direction before said dog carrier completes its movement in the same direction, an automatically operating wedging means adapted to contact with one of said dogs when said dog carrier completes the first half of its movement, and means for returning said wedging means to normal position.

18. In a typewriting machine, the combination of an oscillating dog rocker, an escapement dog movable with and independently of said dog rocker, a spring for moving said dog with said dog rocker in one direction, an automatically operating wedging device for moving said dog with said dog rocker in the opposite direction, means for arresting the movement of said dog in one direction independently of the movement of said dog rocker, means for forcing said wedging device against said dog when said dog rocker reaches the limit of its movement in one direction, and a fixed stop for resetting said wedging device when said dog rocker returns to normal position.

19. In a typewriting machine, the combination of an oscillating dog carrier, two dogs movably mounted upon said dog carrier, means for changing the relative position of both of said dogs with reference to said dog carrier toward the limit of one movement of said dog carrier, a wedging device carried by said dog carrier for returning said dogs with said dog carrier after the completion of said one movement thereof, and means for resetting said dogs upon said dog carrier.

Signed at Syracuse, in the county of Onondaga, and State of New York, this 18th day of May A. D. 1908.
